UNITED STATES PATENT OFFICE.

JOHN A. GROSHON, OF NEW YORK, N. Y., ASSIGNOR OF ONE-HALF TO
MARSHALL T. DAVIDSON, OF BROOKLYN, NEW YORK.

STEAM PUMPING-ENGINE.

SPECIFICATION forming part of Letters Patent No. 711,702, dated October 21, 1902.

Application filed October 25, 1901. Serial No. 80,020. (No model.)

To all whom it may concern:

Be it known that I, JOHN A. GROSHON, a citizen of the United States, residing at New York, in the county and State of New York, 5 have invented certain new and useful Improvements in Steam Pumping-Engines, of which the following is a specification.

My invention relates to horizontal pumping-engines; and my invention consists in the 10 arrangement and construction of the cylinders, frame, and working parts of the pumping-engine in such manner as to greatly reduce the weight of the engine and the space required to assemble it and also reduce the 15 vibration of parts owing partly to its compact form and narrow width and short length over all, as well as to the small number of parts.

My invention is more fully set forth and shown in the accompanying specification and 20 drawings, in which—

Figure 1 is a plan of my pumping-engine. Fig. 2 is a side elevation of the same, partly in section, taken on the line *x x* of Fig. 1. Fig. 3 is a sectional detail view of the pump 25 cross-head, taken on the line *a a*, Fig. 2; and Fig. 4 is a sectional detail view of the engine cross-head and frame on line *b b*, Fig. 2.

Referring to the drawings, A represents a suitable foundation for the pumping-engine, 30 and B represents the steam - cylinders arranged side by side, three cylinders being shown and the engine being either of the three-cylinder compound or triple expansion type, as may be preferred.

35 C represents a suitable form of valve-gearing, shown only on the central cylinder for the sake of simplicity, this valve-gearing being of the automatic-release type and controlled by a fly-ball governor D, the same having 40 a hydraulic attachment E for controlling the speed of the engine in accordance with the pressure in the pump or mains. The features of this combined fly-ball and hydraulic governor are claimed in my copending application, Serial No. 77,065, filed September 30, 1901, and the same will not be herein referred to in detail. Since the valve-gearing itself is 45 not a part of my present invention, its internal construction has not been shown and the same will not be described in detail, as any suitable 50 form of valve - gearing may be used. As

shown, the valve-gearing is operated from an eccentric F on the main shaft G.

The pump-casings H contain cylinders and are suitably connected to each other in the 55 usual manner by piping I with an inlet J for water and an outlet K therefor. The frames connecting the steam-cylinders and pumps are of special construction, designed for lightness and strength and to reduce the space occupied by the engine as a whole, and especially to bring the pumps closer to the steam-cylinders than is obtainable in the ordinary forms of horizontal pumping-engine.

The central engine - frame L is provided 65 with arms L', suitably connected to the central pump-casing, and these arms L' are supported upon pedestals P, while between the pedestals and the central steam-cylinder are pillars O, which serve to steady and support 70 the main frame of the engine. The frames of the engines, as described, are of what may be termed the "girder" type, and the frames connecting the outer steam - cylinders with the outer pump-casings have arms Q connect- 75 ed to the pump-casings H and supported upon pedestals P', with pillars, as before, between the pedestals and steam - cylinders. Other girder connections Q' connect the main portions of the outer frames with the pump-cas- 80 ings. By thus arranging the frames the pump-casing may be brought close up to the pedestals in such manner as to greatly reduce the necessary length of the engine.

The main shaft G is carried in bearings G' 85 in the pedestals P P' close to the inner ends of the pump-casings, while fly-wheels R are arranged on the main shaft and between the pumps. By this arrangement of supporting the main shaft between the engines and 90 pumps with the fly-wheels between the engine-frames the width of the engine over all may be greatly reduced, and a close compact arrangement is provided of light and strong parts, which reduces the weight, and the whole 95 arrangement tends to reduce vibration. The particular form of the engine-frames is not part of my invention, and any suitable form may be used, the castings being made of different shapes, as desired.

100 The cranks R' on the main shaft are preferably set at one hundred and twenty degrees

apart, and connecting-rods T, as shown, connect with the engine cross-heads, while the steam-cylinders are provided with the usual piston-rods T' and pistons T². The pump-cylinders in the pump-chambers are also provided with plungers U and plunger-rods U', connected to cross-heads U². The plungers are preferably single-acting and are driven from connections with the engine cross-heads V in such manner that the strain upon the pump-plungers is compressive, while that on the connections is principally, if not entirely, tensile when pumping is being done. In other words, the work is done with a pull or tension between the engine and pump cross-heads and with a push or compression on the plungers.

Suitable operative connections are made between the engine cross-heads D and pump cross-heads U². As shown, connecting-rods W form these connections. These rods are connected to the engine cross-heads at diagonal points, and they are also connected to the pump cross-heads at diagonal points respectively opposite the points of connection to the engine cross-heads. As shown in Figs. 3 and 4, the rods W are connected to the cross-head V on a diagonal line by arms c, and they are also connected to the cross-head U² of the pump on a diagonal line by arms d. The rods W extend then from the engine cross-heads in the direction of the water end of the engine, one of these rods preferably extending above and the other below the engine-frame in order to clear the main shaft, and they pass through bearings in casings and the pump, respectively, the rods passing through casings or sleeves e, placed within the pump-chambers, so that the rods are not in contact with the water and no stuffing-boxes are necessary where they enter and leave the chambers. By this arrangement of rods it will be seen that all the operative parts of the engine are left clear for operation and the connecting-rods T operate between the rods W, while at the same time the cross-head V is arranged within the engine-frame. As before stated, the pump-plungers are single-acting and the rods W are connected to their cross-heads in such manner that water is only being pumped upon the outstroke of the steam-piston or while the steam-piston is traveling in a direction away from the pumping end of the pump. By this arrangement it will be seen that all the strain on the rods W in pumping is principally tensile, no work being done by the engine when the pump-plunger is filling its cylinder with water, at which time there would be a compression upon the rods. A great deal of the vibration in the rods W is thereby avoided, which also tends to reduce the vibration in the engine. By passing the rods W through the pump-casings vibration is also reduced, space is saved, and the number of parts reduced.

In order to provide a suitable engine cross-head for my pumping-engine, I form the in-

ner sides of the engine-frame with longitudinal ribs or guides X, while grooves or recesses X' are formed in the cross-head to fit the tongues or guides X, so that the cross-head may slide thereon, and I have found this to be an effective construction, enabling me to utilize a very light engine-frame.

It will thus be seen that according to my invention there are a plurality of steam-engines arranged side by side, with a corresponding number of single-acting pumps each opposite one of the engines. Between each steam-engine and pump there is one engine cross-head, because according to my construction but one cross-head is necessary, as I entirely dispense with the second cross-head, which is found in ordinary constructions. Between the cross-heads and pump-chambers is arranged a crank-shaft, and since I have dispensed with the second cross-head the pump-chambers are brought in close proximity to the crank-shaft and bearings, it only being necessary to leave sufficient space between the crank-shaft and pump-chambers to admit of the revolution of the cranks. By this construction it will be seen that I greatly reduce the length of the engine, and by using a plurality of single-acting pumps the effect on the water-column is the same as though the engine were double-acting. Where three steam-engines are used, as in this instance, the cranks are arranged on the crank-shafts one hundred and twenty degrees apart, for by this arrangement the load on the engine is balanced throughout the revolutions, the work being done upon the instroke of the pump-plungers. Fly-wheels are arranged on the crank-shaft between the engine-frames and extending between the pump-chambers, and connecting-rods extend from the engine cross-heads through bearings in the pump-chambers and are connected at the rear of the pump-chambers to cross-heads attached to the pump-plungers, whereby the strain on the said connecting-rods is wholly tensile.

Without limiting myself to the precise details of construction and arrangement shown and described I claim, and desire to secure by Letters Patent, the following:

1. The combination in a steam pumping apparatus, of a plurality of steam-engines side by side, a corresponding number of single-acting pumps each opposite one of the engines, one engine cross-head between each steam-engine and pump, a crank-shaft and bearings therefor between the pump-chambers and cross-heads, the pump-chambers being situated in close proximity to the said crank-shaft and bearings, cranks connected to said crank-shaft and arranged at one hundred and twenty degrees apart, whereby the load on the engine is balanced throughout the revolutions, fly-wheels arranged on the shaft between the engine-frames and extending between the pump-chambers, and connecting-rods extending from the engine cross-heads through bearings on the pump-cham-

bers and connected at the rear of the pump-chambers to cross-heads attached to pump-plungers, whereby the strain on the said connecting-rods is wholly tensile, substantially 5 as set forth.

2. The combination in a steam pumping apparatus, of a plurality of steam-engines side by side, a corresponding number of single-acting pumps each opposite one of the engines, a crank-shaft and bearings therefor between the pumps and engines, and located in close proximity to the pump-casings, the cranks connected with the cross-heads of the engines, and connecting-rods extending from 10 the engine cross-heads through sleeves extending through the pump-casings and connected at the rear and outside of said pump-casings to cross-heads attached to the pump-plungers whereby the strain on said connecting-rods 15 is wholly tensile, substantially as set forth.

3. The combination in a steam pumping apparatus, of a plurality of steam-engines side

by side, a corresponding number of single-acting pumps each opposite one of the engines, a crank-shaft located in close proximity 25 to the pump-casings with the cranks connected to the cross-heads of the engines, plungers extending through the opposite heads of the casings and connecting-rods arranged in pairs diagonally one above and the other below the crank-shaft and extending from the engine cross-heads through the pump-casings and connected at the rear and outside of said pump-casings to cross-heads attached to the pump-plungers, substantially 30 35 as set forth.

In testimony whereof I have signed my name to this specification in the presence of two subscribing witnesses.

JOHN A. GROSHON.
